N. L. MALMGREN

STRUT OR COLUMN

Filed Jan. 12, 1923

FIG. 1. 2. D

FIG. 2. D

FIG. 5.

Inventor
Nels J. Malmgren
By Fred. Elbald, Atty.

UNITED STATES PATENT OFFICE.

NELS L. MALMGREN, OF CHICAGO, ILLINOIS.

STRUT OR COLUMN.

Application filed January 12, 1923. Serial No. 612,301.

To all whom it may concern:

Be it known that I, NELS L. MALMGREN, a citizen of the United States, and a resident of Chicago, in the county of Cook and State of Illinois, have invented an Improved Strut or Column, of which the following is a specification.

This invention relates to struts or columns.

10 Struts or columns embodying my invention and improvements are devised primarily for supporting the temporary floor or platform on which a concrete floor is to be laid, but admit of a wide range of adaptation and use and I do not, therefore, desire to limit myself to any particular use or application thereof.

The object of the invention is to provide a strut or column consisting, in part, of post 20 members of random lengths, which may readily be adjusted to any desired height or length, thus providing for utilizing pieces of timber which by themselves are too short to be available for the purpose 25 and, also, to avoid the necessity and expense incident to cutting new timbers to the exact lengths required.

Broadly stated, a strut or column embodying my invention and improvements 30 comprises a sleeve member, a post member adapted to telescope within said sleeve member and an adjustable stop on said sleeve member, which forms an abutment for the post member.

35 Specifically, the sleeve member of my improved strut or column consists of angle bars and bands secured thereto in spaced relation and which rigidly connect said angle bars, said angle bars being disposed 40 so as to form an unobstructed opening of desired size and shape in cross-section extending lengthwise through said sleeve member, and adjacent angle bars being spaced apart forming longitudinal openings 45 in the lateral sides of said sleeve member, and the abutment stop for engaging said sleeve and post members with each other, consisting of a plate loosely fitted to the opening in said sleeve member formed on 50 which are projections which extend through the openings in the lateral sides of said sleeve member beyond the bands which con-

nect the angle bars forming parts thereof so as to interlock therewith.

The invention also comprises the various 55 other features, combinations of features and details of construction hereinafter described and claimed.

In the accompanying drawings in which my invention is fully illustrated, 60

Figure 1 is a side view of a strut or column embodying my invention and improvements, shown as applied in use for supporting the temporary floor or platform on which a concrete floor is to be laid. 65

Figure 2 is an enlarged, sectional elevation thereof taken substantially on the line 2—2 of Fig. 1.

Figures 3 and 4 are sectional plan views on the line 3—3 and 4—4, respectively, of 70 Fig. 2.

Figure 5 is a perspective view of a plate forming an abutment stop for operatively connecting the members of the column; and

Figure 6 is a fragmentary view illustrating a modification. 75

In the accompanying drawings I have, for purposes of clear and definite illustration, shown a strut or column embodying 80 my invention and improvements as applied in use for supporting a temporary floor or platform on which a concrete floor is to be laid.

Referring now to the drawings, A designates as a whole a strut or post embodying 85 my invention, B the sleeve member thereof as a whole, C the post section thereof as a whole, and D the temporary floor or platform on which the concrete floor, not shown, is to be laid. 90

In what I now consider to be the preferable embodiment of my invention, the sleeve member B consists of four angle bars 1 rigidly connected together by means of bands 2 secured in spaced relation to the exterior surfaces thereof, the relation being such that the inner surfaces of said angle bars will define a substantially square or rectangular opening extending lengthwise through said sleeve member. In practice, 95 the bands 2 will be secured to the angle bars 1 at relatively short distances apart, a desirable interval for usual purposes being about six inches to one foot. The distance 100

will, however, vary with the size of the strut or column. Also, for reasons presently apparent, the extreme bands 2 are secured to the angle bars 1 at an appreciable distance 6 from the ends of said angle bars, usually from six inches to one foot.

While I consider the use of continuous bands 2 for connecting the angle bars 1 to be preferable, I do not desire to limit myself thereto, as other forms of connecting means could readily be substituted for said bands by mechanics skilled in the art without the exercise of invention. For example, 10 separate straps might be substituted for the continuous bands 2.

The post member C preferably consists of a timber of substantially the same shape in cross section as the opening through the sleeve member B and which is of such size 20 that it will telescope into the sleeve member B, being loosely fitted thereto.

As shown, the angle bars 1 are secured together in spaced relation to each other so that openings 3 will be formed in the lateral 25 sides of the sleeve member, the end sections of said openings beyond the extreme connecting bands 2 defining slots 4 adapted to receive the joists 5 which form the temporary supports for the floor joists 6 of the 30 temporary floor D.

In use, the sleeve member B and post member C of my improved strut or column are adapted to be secured together to form a strut or column of desired length, by means 35 of plates 7 which conform substantially to the shape in cross-section of the opening through the sleeve members B and are loosely fitted thereto and formed on which are lugs or projections 8 which extend 40 through the openings 3 in the lateral sides of said sleeve section outwardly beyond the portions of the bands 2 which extend across said openings, so as to interlock therewith.

To render the plates 7 interchangeable so 45 that they may be engaged with different bands 2, said plates are so proportioned that they may be inserted into the opening in the sleeve section B through the lateral openings 3 in said sleeve member between adjacent 50 connecting bands 2, thus rendering said abutment plates interchangeable and permitting the post member C to enter the sleeve member B a greater or less distance depending upon the length of the post member C and 55 the designed over-all length of the column A.

The particular advantage of this feature of my improved strut or column is that the post member C may be made of timbers of random length, thus providing for the use 60 of pieces of timber which might otherwise be of little or no value, instead of making said struts or columns of new timbers cut to proper length.

In practice, also, plates 7 will also preferably be used to provide a supporting surface

of considerable area for the joists 5, instead of resting said joists directly upon the relatively narrow edges of the bands 2, the plates 7 for supporting said joists 5 resting upon the top sides of the extreme upper bands 2 instead of at the under sides thereof, as in the case of the plates which form the abutment stops for connecting the sleeve and post members B and C.

To provide for accurately adjusting the 75 tops of the columns 5 to bring them to the proper level, the lower ends of the post members C preferably rest upon wedges 9 which in turn rest upon a suitable support or foundation indicated at 10.

When the over-all length of the strut or column, as assembled for use, is either longer or shorter than can be taken up by the wedges 9, to adjust the tops of the joists 5 to the desired level, my invention contemplates either cutting a short piece off from the ends of the post members C, when too long, or inserting a piece of proper length at the upper end of said post member, if too short. In the drawings, in which the 90 post member C is assumed to be too short, said post member is shown as lengthened by a block 11 inserted between the upper end of said post member and the stop plate 7.

Instead of supporting the joists 5, or other 95 load, directly upon the upper end of the sleeve member B, my invention contemplates equally making the strut or column A of two separate post members C connected by a sleeve member B.

This modification is shown in Fig. 6 of the drawings, in which C¹, C² indicate the post members, B¹ the sleeve member which connects said post members, and 7¹ a stop plate against which the upper end of the lower post member C¹ abuts, and the lower end of the upper post member C² rests, said sleeve member maintaining said post members in alignment and the stop plate 7¹ securing said sleeve member in position relatively 100 to the connected ends of said post members.

I claim—

1. A strut or column comprising a sleeve member consisting of flanged longitudinal members, transverse members which rigidly 115 connect said longitudinal members together in spaced relation forming openings in the sides of said sleeve member across which said transverse members extend, a post member adapted to telescope within said sleeve member, and a stop plate adapted to be inserted into said sleeve member with parts thereof projecting through longitudinal openings in the sides of said sleeve member so as to interchangeably interlock with 120 transverse members of said sleeve, substantially as described.

2. A strut or column as specified in claim 1, in which the abutment plates are removable and replaceable through the openings 125

in the sides of the sleeve member, substantially as described.

3. A strut or column as specified in claim 1, in which the extreme upper and lower transverse members of the sleeve are secured to the longitudinal members thereof at a distance from their ends, defining slotted openings in the ends of said sleeve member

adapted to receive members of a temporary structure supported by said strut or column, substantially as described.

In witness that I claim the foregoing as my invention, I affix my signature this 8th day of January, A. D. 1922.

NELS L. MALMGREN.
